UNITED STATES PATENT OFFICE.

PINK C. RABB, OF STOCKTON, CALIFORNIA.

ENVELOPE.

Application filed February 2, 1918, Serial No. 215,119, Renewed July 27, 1922. Serial No. 577,930.

To all whom it may concern:

Be it known that I, PINK C. RABB, a citizen of the United States, residing at Stockton, in the county of San Joaquin and State of California, have invented new and useful Improvements in Envelopes, of which the following is a specification.

This invention relates to envelopes, the object in view being to provide an envelope having means whereby it may be easily and quickly opened to enable the contents thereof to be removed.

With the above and other objects in view, the invention consists in the novel construction, combination and arrangement of parts, as herein described, illustrated and claimed.

In the accompanying drawing,

Figure 1 is a face view of the envelope showing the opening means therefor.

Figure 2 is an edge view of the envelope showing the location of the opening strip and the primarily open corner portions of the envelope edge occupied by the opening device.

The envelope designated at 1, may be made of any suitable material, such as paper, and the end, bottom and sealing flaps may be of any usual or preferred shape. However, in the preferred embodiment of this invention, one of the end flaps designated at 2 is made shorter than the other end flap 3 and terminates at the points 4 so as to leave openings 5 of approximately a half or three-fourths of an inch in length.

Pasted under and within the fold of the end flap 2 is an envelope opener consisting of a short section of string 6, one end 7 of which is left projecting but not of sufficient length to reach to the extreme corner 8 of the envelope. Therefore, the projecting end

7 of the string can not be caught between other envelopes or objects which would probably result in tearing open the end of the envelope and allowing the contents of the envelope to be spilled therefrom. 45

In operation, the envelope is grasped between the thumb and fore finger of one hand, at the sealed or opposite end of the string 6. The projecting end of the string is then grasped between the thumb and fore finger 50 of the other hand and pulled sharply away from the body of the envelope. As a result, the folded portion of the short end flap 2 is severed between the primarily opened portions 5 resulting in a complete opening of 55 the end of the envelope to which the string 6 was previously attached.

I claim:

An envelope comprising a sheet folded longitudinally to define front and back 60 panels, a sealing flap formed at one longitudinal edge of the front panel and foldable onto the back panel, an end closure flap formed on one end of the front panel and sealed onto the back of the back panel, and a flap formed on the other end of the front panel and cut back from the corners thereof whereby to leave free spaces between the corners of the last named flap and the corners of the front panel, and a flexible 70 opening string pasted within and extending throughout the length of the fold of said last named flap and having a projecting free end portion terminating short of the adjacent corner of the envelope, said last named 75 flap being secured against the back of the back panel.

In testimony whereof I affix my signature.

PINK C. RABB.
